UNITED STATES PATENT OFFICE.

EDWIN H. BELL, OF CHICAGO, ILLINOIS.

TIE-PLATE.

1,001,921.

Specification of Letters Patent. Patented Aug. 29, 1911.

Application filed May 16, 1910. Serial No. 561,739.

To all whom it may concern:

Be it known that I, EDWIN H. BELL, a citizen of the United States, and a resident of Chicago, in the county of Cook and State 5 of Illinois, have invented certain new and useful Improvements in Tie-Plates; and I do hereby declare that the following is a full, clear, and exact description thereof, reference being had to the accompanying 10 drawings, and to the letters of reference marked thereon, which form a part of this specification.

This invention relates to improvements in tie plates adapted to rest on wooden rail- 15 way ties beneath the rails and to be used in connection with shouldered lag screws or screw spikes.

The invention consists of the matters hereinafter described and more particularly 20 pointed out in the appended claims.

In the use of screw-threaded spikes the longitudinal wave motion communicated to the rails by the advancing train, tends to draw the spikes a short distance out of the 25 tie. In the case of the ordinary spike, this movement of the rail does actually withdraw the spike a short distance so as to raise the spike heads above the rail flange which permits the rail to respond to this 30 movement. In the case of the screw spike, however, this wave motion, as it cannot withdraw the spike on account of its screw-threaded attachment to the tie, tends to turn back the head of the spike, or to ro- 35 late it about a horizontal axis.

The object of the present invention is to provide a construction of tie plate and a washer interposed between the tie plate and screw head to prevent the said movement of 40 the spike head about a horizontal axis away from the rail flange and to prevent the washer from rotating about a vertical axis.

In carrying out my invention I provide a tie plate having longitudinal ribs on its up- 45 per surface and a rail abutting shoulder or shoulders and a washer underlying the spike head and having locking engagement with the upper surface of the tie plate to prevent its rotation about a horizontal axis 50 and locking engagement against the rail flange to prevent its rotation about a vertical axis.

In the drawings:—Figure 1 is a perspective view of a tie plate. Fig. 2 is a vertical 55 section through a tie plate such as is shown in Fig. 1 located on a tie below the rail and

secured in place by means of screw spikes. Fig. 3 is a perspective view of a washer which underlies the shouldered head of the spike and rests on the tie plate. Fig. 4 is a cross-section through Fig. 2 on the line 4—4 thereof. Fig. 5 is a vertical section through Fig. 4 on the line 5—5 thereof. Fig. 6 is a perspective view of a tie plate provided with a single rail abutting shoulder. Fig. 7 is a perspective view of a tie plate with the rail abutting shoulders arranged in a different manner. Fig. 8 is a longitudinal section of the tie plate shown in Fig. 7, the tie plate being in this case anchored to the tie and underlying the rail. Fig. 9 is a cross-section through Fig. 8 on the line 9—9 thereof. Fig. 10 is a perspective view of the type of washer adapted to be used with the tie plate shown in Fig. 7. 75

In the drawings, A indicates the rail, B, the rail base flange, and C, the tie.

D is the tie plate and E indicates the lag screws by means of which the tie plate and rail are anchored to the tie. The lower 80 face of the tie plate D is flat while its upper face is provided with rounded, longitudinal, parallel ribs D¹ at each side of which are located parallel, longitudinal grooves D². In that form of plate illustrated in Figs. 1 85 to 5, there are provided near one end of the plate two rail abutting shoulders F, F which project upwardly from the adjacent central ribs D¹, D¹, and have vertical, rail abutting faces f, f. G, G are holes formed 90 through the plate centrally of the outer ribs, at each side of said shoulders, with their inner curved edges tangential to the vertical faces f of the shoulders F, F. Similar holes G¹, G¹ for screws are provided on the 95 opposite end of the plate. The screw spikes E are provided with shouldered heads e, the under sides of which are conical as shown at e¹.

J is a U-shaped washer which is inter- 100 posed between the head of the spike and the upper face of the tie plate and which is of such thickness that when in place its upper face will be in substantially the same plane as the top surface of the outer margin of 105 the rail base flange. The washer J is provided on its upper surface with a conical depression j adapted to receive the under conical face e¹ of the shouldered head e of the screw. The under surface of said 110 washer is provided with a transversely curved recess j¹ to fit the top of the rib

D^1 and with parallel ribs j^3 adapted to engage in the grooves D^2 on each side of said rib. The outer, longitudinal edges j^2 of the washer are curved in vertical section to fit 5 the rounded surface of the shoulder F adjacent the groove D^2 . The free ends J^1 of the washer are squared off and are adapted, when in place, to abut against the edge of the rail flange and lock the washer against 10 rotation about its vertical axis. The shape of its under surface, which conforms to the top face of the tie plate, together with the edge, which engages the rounded surface of the shoulder F , locks the washer against all 15 movement about its horizontal axis.

The two shoulders F , F may be replaced by a single shoulder F^2 , as indicated on the plate illustrated in Fig. 6, without changing the construction of the other parts of 20 the device.

In Figs. 7 to 10, is shown a construction in which the rail-abutting shoulders F^4 , F^4 project upwardly from the outer longitudinal ribs D^1 , D^1 . A single opening G^2 25 for the spike is, in this case, located midway between the two shoulders, with its inner edge tangential to the vertical faces f of said shoulders, as before. The groove D^2 , separating the middle ribs, is not continued beyond the screw hole G^2 , there being 30 but a single wide rib D^3 at that point. The U-shaped washer K is provided on its upper surface with a depression k adapted to fit the underside of the shouldered head of 35 the spike and on its under surface with a flattened face k^1 to fit the upper face of the rib D^3 . The curved longitudinal edges k^2 of the washer engage the opposing, rounded edges of the shoulders F^4 , and the ribs k^3 engage 40 the grooves D^2 beyond said shoulders. The spikes on the opposite sides of the rail are provided with washers K^x which are in every way similar to those above described, but in the examples illustrated, where the 45 rail-abutting shoulders are omitted on that side of the rail, said washers engage the ribs and grooves in the tie plate only. If desired, the rail-abutting shoulders may be provided on both sides of the rail.

50 I claim as my invention:

1. In combination with a rail, a tie-plate provided with a rail-abutting shoulder, a screw-threaded spike abutting against the rail flange and located adjacent the rail- 55 abutting shoulder, said spike being provided

with a shouldered head adapted to anchor said rail and tie-plate, a washer of substantially the thickness of the margin of the rail flange interposed between the shouldered head of said spike and the tie-plate, 60 said washer forming a seat for said shouldered spike-head exterior to the rail flange and being provided with means having engagement with said tie-plate and with means having lateral engagement with said 65 rail-abutting shoulder.

2. In combination with a rail, a tie-plate provided with a rail-abutting shoulder, a screw-threaded spike abutting against the rail flange and located adjacent the rail- 70 abutting shoulder, said spike being provided with a shouldered head adapted to anchor said rail and tie-plate, a U-shaped washer of substantially the thickness of the margin of the rail flange interposed between the 75 shouldered head of said spike and the tie-plate with its free ends engaged against the rail flange and forming a seat for said shouldered spike-head exterior to the rail flange, said washer being adapted for engagement with the upper surface of said tie-plate, and having a lateral edge adapted for engagement with said rail-abutting shoulder.

3. In combination with a rail, a tie-plate 80 provided in its upper surface with longitudinal ribs and grooves and with a rail-abutting shoulder, a screw-threaded spike abutting against the rail flange and located adjacent the rail-abutting shoulder, said spike being provided with a shouldered head 85 adapted to anchor said rail and tie-plate, a U-shaped washer forming a seat for said shouldered head exterior to the rail flange with its free ends abutting against said rail 90 flange, said washer being recessed on its upper face to receive the shouldered head of said spike and having its lower face conformed to fit the ribbed and grooved upper 95 face of the tie-plate, and said washer having 100 vertically curved edges adapted to engage laterally against said rail-abutting shoulder.

In testimony, that I claim the foregoing as my invention I affix my signature in the presence of two witnesses, this 11th day of 105 May, A. D. 1910.

EDWIN H. BELL.
